UNITED STATES PATENT OFFICE.

EDWIN QUIN BANGS, OF RACINE, WISCONSIN.

MEANS FOR INTRODUCING AIR INTO FURNACES.

1,242,124.

Specification of Letters Patent.

Patented Oct. 9, 1917.

Application filed July 30, 1915. Serial No. 42,738.

To all whom it may concern:

Be it known that I, EDWIN QUIN BANGS, a citizen of the United States, residing at Racine, in the county of Racine and State 5 of Wisconsin, have invented certain new and useful Improvements in Means for Introducing Air into Furnaces; and I do hereby declare the following to be a full, clear, and exact description of the invention, such 10 as will enable others skilled in the art to which it appertains to make and use the same.

My invention relates to means for introducing air into furnaces, and more particularly to that class where coal is used as 15 fuel.

A further object is to so position the attachment that the air will be introduced into the furnace near the combustion chamber 20 at a point above the fire box.

A further object is to provide means for distributing the air as it is introduced into the furnace, etc.

And a further object is to provide means 25 for controlling the introduction of the air.

Other objects and advantages will be hereinafter set forth and more particularly pointed out in the accompanying specification.

30 In the accompanying drawings which are made a part of this application,

Figure 1 represents, in side elevation, partly broken away and in section, a furnace provided with my improved means for introducing air.

Fig. 2 represents, in elevation, the inner end of my air introducing pipe section.

Fig. 3 represents, in elevation, the outer end of the same pipe section.

40 Like reference characters mark the same parts in all of the figures.

1 indicates a furnace inclosed by an outer wall *g* and within the furnace is an inner wall *h* within which are the fire box 2 below 45 and the combustion chamber 3 above.

Within a space *i* between the inner and outer walls is a vertical box or cylinder *a* which, near its upper end, is connected with the combustion chamber 3 by a horizontal 50 pipe *b*, and in line with said pipe *b* a second horizontal pipe *c* connects the box with a vertical smoke pipe *d*, said pipe *c* being provided with a damper *e* and the smoke pipe *d* with a damper *f*.

55 The lower end of the cylinder *a* com-

municates with the lower end of the smoke pipe *d* through a third horizontal pipe 4 which passes through the outer wall *g* of the furnace.

By opening the damper *e* and closing the 60 damper *f*, the products of combustion will be caused to pass through the pipe *b*, across the box *a*, through pipe *c* and through the smoke pipe *d*, but by closing damper *e* and opening damper *f*, the products will be 65 caused to pass through pipe *d*, downward in box *a*, through pipe 4, and up and through the smoke pipe *d*.

A horizontal cylindrical pipe section 5 is introduced through the outer end wall of 70 the pipe 4 to a point adjacent to the point of passage of said pipe 4 through the outer wall of the furnace, said pipe section having heads 6 and 7 at the inner and outer ends thereof respectively, said heads having 75 perforations 8 and 9 respectively, the perforations 9 being provided for the admission of air into the pipe section, while the perforations 8 are designed to divide the air and discharge it in small streams into the products of combustion, while passing from the combustion chamber to the smoke pipe, thereby causing the air to thoroughly mingle with the gas arising from the coal and passing down through box *a*, through pipe 4, 80 and smoke pipe *d*.

The amount of air admitted into the pipe section is regulated by means of a valve 10, and if desired, a plurality of baffle plates 11 may be provided interiorly of the pipe section to interrupt and retard the flow of the air through the pipe section.

By introducing the air through the pipe 4 and box *a* into the furnace or stove at a point above the fire, the oxygen contained 95 in the air will cause the gas from the coal to immediately ignite before entering the smoke pipe, thus obtaining the additional heat, which under other circumstances, would escape through the smoke pipe.

It will further be seen that heat can be quickly obtained by the use of this device, as when the fire is first started or a new supply of coal is introduced into the fire box, the gases arising from the coal will ignite 105 and rapidly heat parts coming in contact therewith, while under ordinary circumstances, it is necessary for the fresh coal to be fully ignited before the highest efficiency of heating qualities can be obtained.

100

105

110

When the draft is fixed to cause the products of combustion to pass downward through the box α , said box serves as an auxiliary or secondary combustion chamber.

5 It will further be seen that by introducing the pipe section in the pipe 4, as shown, the air will be superheated while passing through the pipe section and by placing baffle plates in a short pipe section, the 10 passage of air will be sufficiently retarded to attain the necessary heated condition before being introduced into the gases.

By introducing the air into the furnace in the manner shown, it will cause the gas 15 to ignite immediately upon arising and before it has a chance to leave the furnace or accumulate in the combustion chamber, and in view of the increased heating capacity, a forced draft, required under ordinary circumstances, is eliminated, the coal burning 20 under normal conditions, thus obtaining better consumption of the coal with less ash.

And it will further be seen that a heating plant of insufficient size to produce the necessary heat under ordinary circumstances, 25 can be brought up to the proper heating capacity with the use of my device without increasing the consumption of coal and by reason of a less intense heat in the fire box 30 the life of the fire box and grate will be correspondingly increased.

Having thus fully described my invention what I claim as new and desire to se-

cure by Letters Patent of the United States is:—

In a furnace comprising an inner wall inclosing a combustion chamber, and an outer wall inclosing a space surrounding the combustion chamber, means for supplying air to the furnace, comprising a vertical inner box located in the space between the inner and the outer wall, a horizontal pipe connecting the inner box near its upper end with the combustion chamber, an outer vertical smoke pipe, a second horizontal pipe 40 extending through the outer wall and connecting the inner box near its upper end with the smoke pipe, a third horizontal pipe extending through the outer wall and connecting the lower end of the inner box with the lower end of the smoke pipe, a damper in the second horizontal pipe, a damper in the smoke pipe between the second and third horizontal pipes, and a pipe section projected through the outer end wall thereof into the third horizontal pipe and having openings in its ends to permit of the passage of the outer air.

In testimony whereof I have signed my name to this specification in the presence of 60 two subscribing witnesses.

EDWIN QUIN BANGS.
